STAND FOR HOLDING INTRAVENOUS FLUID CONTAINERS OR THE LIKE

Axel E. F. Johnson, Cincinnati, Ohio, assignor to American Hospital Supply Corporation, Evanston, Ill., a corporation of Illinois

Application July 15, 1955, Serial No. 36,986

Term of patent 14 years

(Cl. D33—8)

Fig. 1 is a perspective view of a stand for holding intravenous fluid containers or the like, showing my new design,

Fig. 2 is a top plan view,

Fig. 3 is a side view in elevation, and

Fig. 4 is a front view in elevation.

The screw shown on the lower portion of the base in Figure 4 has been omitted from Figure 3 for purposes of illustration.

I claim:

The ornamental design for a stand for holding intravenous fluid containers or the like, as shown and described.
